SLIP ELEVATOR

Forrest Joseph Young, Los Angeles, Calif., assignor, by mesne assignments, to The National Superior Company, Toledo, Ohio, a corporation of Delaware

Original application March 8, 1933, Serial No. 660,030. Divided and this application October 3, 1933, Serial No. 691,956

19 Claims. (Cl. 24—263)

This invention relates to elevators of the side door type including slips for gripping pipe, casing or the like as utilized in the drilling formation or operation of wells, particularly oil wells. This 5 invention is related to an improvement over the structures as disclosed in the Letters Patent No. 1,920,617 granted August 1, 1933, for Door type slip elevator, and in the co-pending application of Forrest Joseph Young, et al., Serial No. 610,044, filed May 9, 1932, for Door type slip elevator.

This application is a division of the co-pending application of Forrest Joseph Young, et al., for Door type slip elevator, Serial No. 660,030, filed March 8, 1933.

15 An object of this invention is to provide a well elevator of the door type in which there is provided an improved form of latching means for the door or gate and in which latching means there is provided a means enabling the easy and ready release of the gate in the event the slips of the elevator do not become released when it is desired to remove the elevators from the pipe or casing.

Another object of this invention is to provide 25 a latch releasing means having a novel construction which permits carrying extremely high pressures without requiring the structural components of undue proportions.

Another object of this invention is to provide 30 a latch releasing means for the gate of a door type slip elevator which includes a means permitting the adjustment of the latch for the door or gate of the elevator.

Another object of this invention is to provide a 35 door type slip elevator which includes slips adapted to be actuated by yieldably mounted abutment or setting means which permit the casing collar of the drill stem supported by the elevator to set the slip into engagement with the casing and yet prevent the total casing load being carried through the drilling or casing collar.

Another object of this invention is to provide an improved form of slip setting means in a slip 45 type elevator for setting the slips into engagement with the casing or drill pipe, which means does not require the coaction of a shoulder or abutment on the casing or drill pipe surface.

Other objects and advantages of this invention 50 it is believed will be apparent from the following detailed description of a preferred embodiment thereof as illustrated in the accompanying drawings.

In the drawings:

Figure 1 is a top plan view of a door type slip 55 elevator embodying my invention.

Figure 2 is a front elevation thereof.

Figure 3 is a horizontal sectional view of the elevator taken substantially on the line 3—3 of Figure 2, illustrating the elevator with the lifting links or balls removed.

5

Figure 4 is a vertical sectional view taken on the line 4—4 of Figure 1.

Figure 5 is a vertical sectional view taken on the line 5—5 of Figure 1.

Figure 6 is a vertical sectional view of a modified form of well elevator embodying my invention.

Figure 7 is a horizontal sectional view taken substantially on the line 7—7 of Figure 6.

Figure 8 is a horizontal fragmental sectional view taken substantially on the line 8—8 of Figure 4.

Figure 9 is a fragmental elevation of a slip showing a modified form of my invention.

Figure 10 is a fragmental elevation of a slip 20 illustrating a further modification embodying my invention.

In the preferred embodiment of my invention as illustrated in the accompanying drawings, I 25 indicates the body of a well elevator having elevator link or bail-receiving ears 2 for the reception of any desired form of elevator links or balls 3. Pivotedly secured to one side of the elevator body 1 on a hinge pin 4 is a gate 5. The gate 5 is supported at its respective ends so that 30 the portion of the load received from the drill stem or casing supported by the elevator is transmitted to the body 1.

In order to accomplish this, the free end of the elevator gate 5 is undercut to provide a supporting shoulder 10 which is adapted to rest or seat upon a seat or shoulder 8 formed on the supporting plug 9 of the body 1. At its pivoted end the gate 5 is supported upon a shoulder 9a formed at the lower portion of the hinge recess 10a into 40 which the hinge cylinder of the gate 5 is fitted.

Means are provided for latching the gate 5 in closed position, which means preferably includes a yoke type latch 6 which is pivotally secured to the body by a yoke hinge pin 1. The yoke type 45 latch 6 is illustrated as being of substantially the same construction as is illustrated in the two co-pending applications of Forrest Joseph Young, et al., above referred to and passes over the free end of the gate 5 and includes a latch pin 42 50 which extends horizontally through the handle portion 41 of the latch 6 to fit within a latch pin recess 23 formed in the end of the releasing lever 19. A spring pressed actuating arm 43 is pivotally supported within and protected by the han- 55

idle 41 and provides the means for actuating the latch pin horizontally.

As the elevator embodying my invention incorporates tapered slips 11 within its bore for engaging and supporting the drill stem or pipe, it becomes desirable at many times to have means for releasing the latch 6 when the slips fail to release from the drill stem casing or pipe when the load is relieved off from the slips 11, and in order to accomplish this result and to permit a slight release of the latch yoke 6 so that the slips may move outwardly away from the drill stem to a point where they will release under the influence of their supporting structure, I prefer to provide a releasing lever 19 which is interposed between the free end of the gate 5 and the latch 6 to provide the latching surface 22 in which the latch pin recess 23 is formed. The releasing arm 19 is pivotally supported at the free end of the gate upon a bearing pin 20 which has its axis located approximately in a vertical plane coincident with the plane of the inner side face 21 of latch yoke 6. The releasing lever 19 is positioned between spaced ears 24 formed on the gate and within which is retained the bearing pin 20. The pin passes through an ear or lug 25 formed on the lever 19, the lug fitting within a recess 26 provided in the gate to retain the lever on the gate at the latch end. The latch pin 20 has a bearing contact with the gate for substantially half of its circumference between the ears 24 and the recess 26 and a bearing contact along the face of the lever 19 for substantially the other half of its pin circumference.

This construction provides a substantial bearing area between the gate pin and lever to connect the reaction developed in the load transmitted to the gate by the wedging action of the slips 11 between the pipe and the elevator. The lever 19 is curved to approximately the exterior contour or configuration of the body 1 and terminates at its free end with a bolt hole 27 through which a bolt or stud 28 is passed. The stud 28 is threaded into a boss 29 formed on the gate 45 5 of the elevator and at its outer end is a threaded nut 30 for clamping the free end of the releasing lever 19 to the gate of the elevator.

A handle 31 is preferably cast integral with the releasing lever 19 to provide a handle for the operation of the gate 5. Formed on the inner face of the releasing lever 19 is a boss 32 which is in position to engage a corresponding boss 33 formed on the outer face of the gate 5. The clearance or relative positions of the bosses 32 and 33 will determine the position of the face 22 of the releasing lever 19 with relation to the latch face 21 of the yoke 6 when the nut 30 is threaded to clamp the releasing lever 19 in position. It is therefore possible, when wear occurs between the faces 21 and 22, to re-establish a correct latching relation between these surfaces by filling the contacting faces of the bosses 32 and 33, thereby permitting the face 22 to move more perfectly into contact or latching relation with the face 21 on the screwing up of the nut 30. By this means an easy adjustment is provided for the latch means for the gate 5 of the elevator.

The slips 11, as herein illustrated, are of substantially the same construction as illustrated in the co-pending applications of Forrest Joseph Young, et al., above referred to in that it is preferred that the body 1 and gate 5 be formed to provide a stepped tapered axial bore within which the correspondingly tapered and stepped seg-

mental slips are positioned in the manner as specifically set forth in the co-pending applications above referred to. As shown in said co-pending applications above set forth, the slips are mounted within the elevator body 1 and gate 5 on guide pins 12 which cooperate with compression springs 13 to normally hold the slips in a released position.

In the modification of my invention as illustrated in Figures 1 to 4, the upper ends of the slips 11 are provided with bumper segments 14 which are fitted within arcuate recesses 15 formed in the upper ends of the bodies on the slips 11.

In order to provide a yieldable connection between the bumper segments 14 and the bodies 15 of the slips 11 blocks of rubber 16, or other resilient material or any other preferred form of yieldable element, is inserted within the recesses 15 on the under side of the bumper segments 14 to normally urge the bumper segments 20 14 upwardly away from the upper end of the slips 11. The bumper segments 14 are slipped into the slips 11 from the sides thereof and thin plates 17 are welded to the sides of the slips 11 over the recesses 15 to hold the bumper segments in place after they have been mounted in position.

In order to prevent one slip 11 from advancing ahead of the other slips due to the non-concentricity of the drill stem or pipe with relation to the bore of the elevator or other reason, the slips 11 are preferably linked together by means of interlocking lugs 18 (Figure 8) which fit within complementary recesses 18a formed on the lateral faces of the adjacent slips 11.

In the modification of my invention as illustrated in Figures 6 and 7, the slips 11a are illustrated as formed with yieldable bumper elements or bumper plungers 14a positioned so as to extend laterally from the face of the slips 11a to seat the slips 11a into engagement with the periphery of the drill stem pipe or casing independently of the collar of the drill stem pipe or casing, thus enabling the structure to be utilized in connection with flush type drill stems or pipe having no projections or collars upon its exterior periphery.

The bumper plunger 14a is mounted within recesses 15a formed within the upper end of the slips 11a and are normally urged outwardly into pipe engaging position by means of springs or yieldable members 16a.

In order to limit the outward extent of the plungers 14a stop members consisting of cap screws 16a are threaded through the upper ends of the slips 11a to fit within slots 117a formed within the plungers 14a. The outer peripheries of the plunger members 14a are provided with serrated surfaces so as to increase the frictional contact between them and the periphery of the pipe in order to insure the setting of the slips as the pipe is lowered or the elevator is raised after the gate 5 of the elevator has been closed.

As illustrated in Figures 9 and 10, in order to prevent rotation of the drill stem or pipe within the elevator or to prevent rotation of the elevator with relation to the drill pipe after the gate of the elevator has been closed, it may be preferable to form one of the plungers 14b with its serrated interior periphery formed with vertical rather than horizontally extending serrations, or, as illustrated in Figure 10, the serrations on the inner peripheries of the plungers 14c are formed in oppositely inclined positions which likewise function to prevent rotation of the 75

elevator with relation to the pipe upon relative vertical movement of the pipe and elevator.

In order to perfect the free swinging of the latch yoke 6, I prefer to provide anti-friction bearing means comprising a plurality of balls 45 positioned in race grooves formed around the pins 7 and formed between the upper arm of the yoke 6 and the body 1. In order to assemble the balls 45, I provide a washer plate 46 on the pin 7 between the body 1 and the lower arm of the yoke 6. When the plate 46 is removed, the yoke is lifted vertically an amount equal to the thickness of the space occupied by the washer plate and the balls inserted into the race grooves—the yoke is then lowered into engagement with the balls and the plate 46 assembled preliminary to placing the pin 7 in position. The pin 7 is preferably welded into position with the yoke 6.

Having fully described my invention and the preferred forms that the same may take, it is to be understood that I do not wish to be limited to the details of construction as herein specifically set forth as my invention is susceptible of wide modification without departing from the spirit of my invention as defined in the appended claims.

I claim:

1. In combination with a tube gripping device having a tapered bore, tapered sectional slips mounted within the bore, means for yieldably supporting the slips, yieldably mounted plunger members mounted within recesses in and extending from the vertical face of the slips to engage a pipe within the bore formed by the tapered sectional slips for seating the slips in pipe engaging position within the said bore, and stop means to limit the movement of the plunger members in their extended positions.

2. In combination with a tube gripping device having a tapered bore, tapered sectional slips mounted within the bore, means for yieldably supporting the slips, yieldably mounted plunger members mounted within recesses in and extending from the vertical face of the slips to engage a pipe within the bore formed by the tapered sectional slips for seating the slips in pipe engaging position within the said bore, stop means to limit the movement of the plunger members in their extended position, and one of said plungers being formed with an engaging surface so as to prevent relative rotation of the tube gripping device and the pipe.

3. In combination with a tube gripping device having a tapered bore, tapered sectional slips mounted within the bore, means for yieldably supporting the slips, yieldably mounted plunger members mounted within recesses in and extending from the vertical face of the slips at the upper ends thereof to engage a pipe within the bore formed by the tapered sectional slips for seating the slips in pipe engaging position within the said bore, stop means to limit the movement of the plunger members in their extended position, and the engaging surface of said plungers being formed so as to hold the device and pipe from relative rotation.

4. In a device of the class described, the combination of a body, a gate pivotally supported at one side of the body, a latch member having a plane bearing surface supported at the opposite side of the body and adapted to engage the free end of the gate to hold the gate in closed position, means providing a plane latching surface between the latch member and the gate, adjust-

able means operative between the latching surface means and the gate for varying the effective position of the latching surfaces between the gate and the latch member, and a third means for locking the latch member in latching position.

5. In a device of the class described, the combination of a body, a gate pivotally supported at one side of the body, a latch yoke pivotally supported at the other side of the body and adapted to pass over the free end of the gate, means positioned between the latch yoke and the gate to establish a latch surface for the latch yoke, means for actuating the first named means at times to vary the latching relation between the latch yoke and the gate, latch locking means carried by the latch yoke for maintaining the latch yoke in latched position relative to the gate.

6. In a gate type elevator, the combination of a body, a gate member pivotally supported at one side of the body, a latch member pivotally supported by the body and adapted to pass over the free end of the gate member when in its closed position, means interposed between the latch member and the gate member to vary the relation between the gate member and the latch member, said means including a pivotally mounted element carried by one of the aforesaid members, and pivot bearing means between the said element and its supporting member, said bearing means including a pivot pin positioned between opposing bearing grooves formed on the element and the element supporting member respectively.

7. In a gate type elevator, the combination of a body, a gate member pivotally supported at one side of the body, a latch member pivotally supported by the body and adapted to pass over the free end of the gate member when in its closed position, means interposed between the latch member and the gate member to vary the relation between the gate member and the latch member, said means including a pivotally mounted element carried by one of the aforesaid members, and a pivot pin engaging the said element and element supporting member to retain the former on the latter, said element and element supporting member being provided with opposing bearing grooves which engage said pivot pin.

8. In a device of the class described, the combination of a body, a gate pivotally supported at one side of the body, a latch pivotally supported at the other side of the body and adapted to engage the free end of the gate, auxiliary latch-adjusting means interposed between the latch member and the gate and carried by the latter, means for varying the operative position of the auxiliary latch-adjusting means to adjust the latching relation between the latch and the gate, and a single member interposed between the auxiliary latch-adjusting means and the gate providing a bearing means between said auxiliary member and the gate, and providing also a means for retaining the auxiliary member in position with relation to the gate.

9. In a door type slip elevator, the combination of a body, a gate pivotally supported at one side of the body, the gate and body being formed to provide a tapered opening, slips mounted in the tapered opening to support a pipe therein, means normally acting to move said slips to a retrieved position, a latch pivotally supported at one side of the body and adapted to engage the free end of the gate, means to hold said latch in its latched

position, means positioned between the latch and the gate providing for an adjustable latching relation between the latch member and the gate, and means for adjusting the latter said means to permit limited outward movement of the free end of the gate relative to the body upon failure of the first named means to retrieve the slips when the pipe load is removed from said elevator so as to facilitate the disengagement of the slips from the pipe supported within the opening.

10. In a door type slip elevator, the combination of a body, a gate pivotally supported at one side of the body, the gate and body being formed to provide a tapered opening, slips mounted in the tapered opening to support a pipe therein, means normally acting to move said slips to a retrieved position, a latch pivotally supported at one side of the body and adapted to engage the free end of the gate, means positioned between the latch and the gate providing for an adjustable latching relation between the latch member and the gate, and means for adjusting the latter said means to permit limited outward movement of the free end of the gate relative to the body upon failure of the first named means to retrieve the slips when the pipe load is removed from said elevator so as to facilitate the disengagement of the slips from the pipe supported within the opening, and means for locking the latch in position relative to the free end of the gate.

11. In a device for supporting a well pipe, the combination of a plurality of pivotally connected pipe encircling members relatively movable to surround a well pipe, a latch supported on one of said members and having a latching surface adapted to normally pass over and engage a complementary fixed latching surface on the free end of the adjacent member for holding said members in their closed position around the pipe, said engaging latching surfaces being relatively fixed normally and formed to permit said latch to normally move freely from latched position to unlatched position and vice versa when the members are in their closed position and without affecting the fixed operative relation of said latching surfaces, and means for adjusting at times one of the latching surfaces relative to the other to permit relative pivotal movement between said members.

12. In a device for supporting a well pipe, the combination of a plurality of pivotally connected pipe encircling members relatively movable to surround a well pipe, a latch supported on one of said members and having a latching surface adapted to normally pass over and engage a complementary fixed latching surface on the free end of the adjacent member for holding said members in their closed position around the pipe, said engaging latching surfaces being relatively fixed normally and formed to permit said latch to normally move freely from latched position to unlatched position and vice versa when the members are in their closed position and without affecting the fixed operative relation of said latching surfaces, means for releasably retaining said latch in latched position, and means for adjusting at times one of said latching surfaces relative to the other to permit relative pivotal movement between said members.

13. In a device for supporting a well pipe, the combination of a plurality of pivotally connected pipe encircling members relatively movable to surround a well pipe, a latch pivotally supported on one of said members and having a latching surface normally adapted to swing over and en-

gage a complementary fixed latching surface on the free end of the adjacent member for holding said members in their closed position around the pipe, latch retaining means to hold said latch in the engaged position, said latch surfaces being relatively fixed normally and formed to permit said latch being free to swing to a disengaged position upon release of the latch retaining means without affecting the fixed operative relation of said latching surfaces and with the members in their closed position, and means for adjusting at times the position of the latching surface on the free end of said member relative to the latching surface of said latch.

14. In a device for supporting a well pipe, the combination of a plurality of pivotally connected pipe encircling members relatively movable to surround a well pipe, an element pivotally mounted on one of said members and having a latch engaging face formed thereon near the free end of said member, means to adjustably secure said element fixed on said member, a latch pivotally supported on the free end of the adjacent member having a latching surface adapted to normally pass over and engage the said latch engaging face for holding said members in their closed position around the pipe and without affecting the fixed operative relation of said latching surfaces, said latching and latch engaging surfaces being relatively fixed normally and formed to permit said latch to normally move freely from latched position to unlatched position with said element in its fixed position and with the members in their closed position, and means to selectively adjust said element securing means to vary the relation of the latch engaging face on said element with the element supporting member to permit relative pivotal movement between said members.

15. In a device for supporting a well pipe, the combination of a plurality of pivotally connected pipe encircling members relatively movable to surround a well pipe, said members being formed to provide a tapered seat, slips carried by said members and supported on said seat in pipe engaging position, means acting to move said slips to a retrieved position, a latch supported on one of said members and having a latching surface to engage a complementary fixed latching surface on the free end of the adjacent member for holding said members in their closed position around the pipe, said engaging latching surfaces being relatively fixed normally and formed to permit said latch to normally move freely from latched to unlatched position when the slips are retrieved without affecting the fixed operative relation of said latching surfaces and the members are in their normally closed position, and means for adjusting one of said latching surfaces relative to the other upon failure of the first named means to retrieve the slips when the pipe load is removed from said device so as to enlarge the seat opening and facilitate the retrieval of the slips from the pipe.

16. In a device for supporting a well pipe, the combination of a plurality of pivotally connected pipe encircling members relatively movable to surround a well pipe, said members being formed to provide a tapered seat, slips carried by said members and supported on said seat in pipe engaging position, means acting to move said slips to a retrieved position, a latch supported on one of said members and having a latching surface to engage a complementary fixed latching surface on the free end of the adjacent member for holding said members in their closed position

around the pipe, said engaging latching surfaces being relatively fixed normally and formed to permit said latch to normally move freely from latched to unlatched position when the slips are retrieved without affecting the fixed operative relation of said latching surfaces and the members are in their normally closed position, and means operable prior to the disengagement of the latch to permit relative opening movement of the pipe encircling members upon failure of the slips retrieving when the pipe load is relieved from said device.

17. In a device for supporting a well pipe, the combination of a plurality of pivotedly connected pipe encircling members relatively movable to surround a well pipe, gripping means carried by said members for supporting the well pipe, said means being normally retrievable from gripping engagement with the pipe upon the pipe load being relieved from said device, a latch supported on one of said members and having a latching surface to engage a complementary fixed latching surface on the free end of the adjacent member for holding said members in their closed position around the pipe, said engaging latching surfaces being relatively fixed normally and formed to permit said latch to normally move freely from latched position to unlatched position when the gripping means are moved to non-gripping position without affecting the fixed operative relation of said latching surfaces and the members are in their normally closed position, and means for adjusting one of said latching surfaces relative to the other upon failure of the gripping means releasing when the pipe load is relieved from said device so as to facilitate the releasing of said gripping means.

18. In a device for supporting a well pipe, the combination of a plurality of pivotedly connected pipe encircling members relatively movable

to surround a well pipe, gripping means carried by said members for supporting the well pipe, said means being normally retrievable from gripping engagement with the pipe upon the pipe load being relieved from said device, a latch supported on one of said members and having a latching surface to engage a complementary fixed latching surface on the free end of the adjacent member for holding said members in their closed position around the pipe, said engaging latching surfaces being relatively fixed normally and formed to permit said latch to normally move freely from latched to unlatched position when the gripping means are moved to non-gripping position without affecting the fixed operative relation of said latching surfaces and the members are in their closed position, and means operable prior to the disengagement of the latch to permit limited relative opening movement of the pipe encircling members upon failure of the gripping means being released from its gripping action on the pipe when the pipe load is relieved from said device.

19. In combination with a tube gripping device having a tapered opening, tapered sectional slips mounted within the opening, means for yieldably supporting the slips, undercut arcuate recesses formed in the upper portion of said slips, said recesses extending around the slips and opening on the lateral faces of the slips, segmental elements having a complementary inverted T-shaped cross-section positioned and retained in said undercut arcuate recesses and adapted to be engaged by a projection on the pipe, and resilient means engaging the under side of said elements, and means to close the said openings upon the segmental elements being assembled.

FORREST JOSEPH YOUNG. 40

CERTIFICATE OF CORRECTION.

Patent No. 2,048,209.

July 21, 1936.

FORREST JOSEPH YOUNG.

It is hereby certified that error appears in the printed specification of the above numbered patent requiring correction as follows: Page 1, second column, line 38, for the word "plug" read lug; page 2, first column, line 61, for "filling" read filing; and that the said Letters Patent should be read with these corrections therein that the same may conform to the record of the case in the Patent Office.

Signed and sealed this 6th day of October, A. D. 1936.

(Seal)

Henry Van Arsdale
Acting Commissioner of Patents.
